UNITED STATES PATENT OFFICE.

WELCOME CARPINTER DENNIS, OF OAKLAND, CALIFORNIA.

SHIP GOVERNOR.

Application filed July 19, 1926. Serial No. 123,470.

My invention relates to ship governors and more particularly to the form of governors for preventing the propeller from racing when the ship is travelling in a rough sea. Various devices have been perfected along these lines which make use of a swinging pendulum for controlling the flow of steam to the engines, but they have proven unsatisfactory owing to the continual swinging of the pendulum due to the way in which it was mounted. It is, therefore, an object of my invention to use a pendulum which is controlled entirely by the diving and raising action of the ship and not affected by the vibrations thereof.

Referring to the accompanying drawings which are made a part hereof and on which similar reference characters indicate similar parts,

Figure 1 is a side elevation of a governor with parts broken away for clearness of illustration,

Figure 2, a section on the line 2—2 of Figure 1,

Figure 3, a section on the line 3—3 of Figure 1, and

Figure 4, a section on the line 4—4 of Figure 1.

In the drawings the numeral 10 denotes a base block rigidly secured to the hull of the ship at a point between the boilers and engine thereof. An upright 11 is secured to the base block 10 and stands upwards and is attached to the stem pipe 12, which feeds steam to the engines. A shaft 13 extends through the upright 11 and pipe 12 and carries a disk valve 14 on the end in the pipe 12 while a segment 15 is secured adjacent the opposite end. The segment 15 meshes with a larger segment 16 on the upper end of a pendulum arm 17 mounted to swing on a shaft 18 supported by the upright 11. The lower end of the pendulum carries a bracket 19 which, with the arm 17, forms a fork. The arm 17 and bracket 19 are slotted as at 20 to receive a shaft 21 upon which is mounted the pendulum weight composed of a heavy wheel 22 adapted to rotate between the bracket 19 and arm 17 and a pair of grooved guide rollers 23 which roll on tracks 24 secured to or formed integral with the base 11. A pair of retaining guide rails 25 mounted to lie in the upper portion of the grooves in the rollers 23 to prevent the displacement of the wheel 22.

Adjacent one end of the tracks 24 is a spring bumper 26 mounted in a fixed standard 27 secured to the base 10 while at the opposite end is a similar bumper 28 mounted in an adjustable bracket 29 adapted to slide in a pair of guideways 30 and adjusted by means of a screw 31 and hand wheel or crank 32. The adjustment of the bumper 28 governs the position of the valve 14 when it is closed by the pendulum.

After the ship has been loaded with cargo it is necessary to trim or align the device so that the tracks 24 are perfectly horizontal. This is accomplished by mounting the base block 10 on fulcrums 33 projecting upward from the keel of the ship so that the angle of incidence between the block and ship may be changed. The block 10 carries a bracket 34 threaded to receive a jack-screw 35 which is swivelled into the keel. Turning the screw 35 in one direction will raise the corresponding end of the block 10 while the opposite direction will lower the end of the block.

The operation of the device is as follows:

When the ship is riding on an even keel the pendulum hangs in the normal position shown at N in Figure 1, and the valve 14 is open permitting full steam to pass. Upon encountering a rough sea the bow of the vessel tilts downward which causes the stern to raise and in some instances carrying the propellers out of the sea causing them to race, but the tilting of the ship causes the wheel 22 to roll towards the bumper 28 carrying with it the pendulum arm 17 which through the segments cuts off a portion of the steam to the engines, thereby checking their speed. The wheel 22 remains in the forward position until the bow has raised slightly above the even keel position when the wheel 22 gradually rolls backward against the bumper 26, thereby permitting full steam to enter the engines again. The design of pendulum described does not maintain a constant perpendicular position that would exist with a pendulum having a fixed weight attached thereto, but instead the arm 17 is carried out of the perpendicular position by means of the travel of the wheel 22 on the straight tracks 24. This construction causes a positive movement of the pendulum governed by the inclination of the tracks 24 and not by the jolting of the ship.

It will be obvious to those skilled in the

art that various changes may be made in my device without departing from the spirit of the invention, and I, therefore, do not limit myself to what is shown in the drawings and described in the specification, but only as indicated in the appended claims.

Having thus fully described my said invention, what I claim as new and desire to secure by Letters Patent, is:

1. A governor comprising a pendulum arm, a steam valve controlled by the fulcrum end thereof, a rotating weight journaled in slots in the lower end thereof, guide rollers rotating with said weight and straight guide rails for said rollers, substantially as set forth.
2. A governor comprising a pendulum arm, a steam valve controlled by the fulcrum end thereof, a rotating weight journaled in slots in the lower end thereof, guide rollers rotating with said weight, straight guide rails for said rollers to roll upon, parallel retaining rails for said rollers and bumpers for limiting the travel of said rollers and weight, substantially as set forth.
3. A governor comprising a pendulum arm, a steam valve controlled by the fulcrum end thereof, a rotating weight journaled in slots in the lower end thereof, guide rollers rotating with said weight, straight guide rails for said rollers to roll upon, parallel retaining rails for said rollers and adjustable means to govern the degree of movement of the steam valve, substantially as set forth.
4. A governor comprising a pendulum arm, a steam valve controlled by the fulcrum end thereof, a rotating weight jour-

nalled in slots in the lower end thereof, guide rollers rotating with said weight, straight guide rails for said rollers to roll upon, parallel retaining rails for said rollers and adjustable means to govern the degree of movement of the steam valve comprising a bumper, an adjustable bracket for said bumper, and means for changing the adjustment thereof, substantially as set forth.

5. A ship's governor comprising a pendulum arm, a steam valve controlled by the fulcrum end thereof, a rotating weight journaled in slots in the lower end thereof, guide rollers rotating with said weight, straight guide rails for said rollers to roll upon; a block for supporting the above structure, and means for adjusting the alignment of said block with the position of the ship, substantially as set forth.

6. A ship's governor comprising a pendulum arm, a steam valve controlled by the fulcrum end thereof, a rotating weight journaled in slots in the lower end thereof, guide rollers rotating with said weight, straight guide rails for said rollers to roll upon, a block for supporting the above structure, and means for adjusting the alignment of said block with the position of the ship, comprising a fulcrum between said block and said ship, and a jack screw carried by said block and swiveled into said ship, substantially as set forth.

In witness whereof, I have hereunto set my hand at Oakland, California, this 28th day of June, A. D. nineteen hundred and twenty-six.
